UNITED STATES PATENT OFFICE

WILLIAM F. BISLEY, OF CHICAGO, ILLINOIS, ASSIGNOR TO CHICAGO FLEXIBLE SHAFT COMPANY, OF CHICAGO, ILLINOIS, A CORPORATION OF ILLINOIS

DESIGN FOR A CLOCK CASE

Application filed November 23, 1931. Serial No. 41,813. Term of patent 14 years.

To all whom it may concern:

Be it known that I, WILLIAM F. BISLEY, a citizen of the Dominion of Canada, residing at Chicago, in the county of Cook and State of Illinois, have invented a new, original, and ornamental Design for a Clock Case, of which the following is a specification, reference being had to the accompanying drawings, forming part thereof.

In the drawings—

Figure 1 is a front view of a clock case showing my new design, and

Fig. 2 is a side view thereof.

I claim:

The ornamental design for a clock case substantially as shown.

WILLIAM F. BISLEY.
